[57] CLAIM

The ornamental design for a sandal, substantially as shown and described.

DESCRIPTION

FIG. 1 is a right side elevational view of a sandal showing my new design;

FIG. 2 is a bottom plan view as taken from line 2—2 of FIG. 1;

FIG. 3 is a top and front perspective view thereof;

FIG. 4 is a top and front perspective view of another embodiment of my new design of FIGS. 1-3, the bottom being identical to FIG. 2;

FIG. 5 is a right side perspective view of FIG. 4.

FIG. 3

FIG. 2

FIG. 4

FIG. 5
